MICROMETRIC GAUGE WITH ILLUMINABLE SCALE

Paul Himmelsbach and Albert Baab, Bad Kreuznach, Germany, assignors to Jos. Schneider & Co. Optische Werke, Bad Kreuznach, Germany, a corporation of Germany

Filed Apr. 12, 1963, Ser. No. 74,409

Claims priority, application Germany Jan. 24, 1963

Term of patent 14 years

(Cl. D52—6)

Fig. 1

Fig. 2

FIG. 1 is a front perspective view showing the front, top and one side of a micrometric gauge with illuminable scale embodying our new design; and

FIG. 2 is a rear perspective view illustrating the back, bottom and other side of the gauge.

We claim:

The ornamental design for a micrometric gauge with illuminable scale, as shown.
